UNITED STATES PATENT OFFICE

ROBERT F. BRACKE, OF CHICAGO, ILLINOIS, ASSIGNOR TO CURTIS B. CAMP, TRUSTEE,
OF GLENCOE, ILLINOIS

CARBURETOR

Application filed July 25, 1929. Serial No. 380,783.

My invention relates to improvements in carburetors.

An object of my invention is to provide an improved carburetor for internal combustion engines.

Another object is to provide a carburetor which because of its unusual compactness and ease of manipulation, is particularly adapted for use on portable engines such as 10 are used to drive mechanical household appliances, or small machinery in home or shop.

Another object is to provide a carburetor which does not choke up and stop the engine when the manually operable choke used 15 in starting is inadvertently held in full closed position after the engine is started.

A further object is to provide a carburetor of the fuel lift type in which fuel is lifted 20 directly from the main fuel supply tank for discharge through the fuel nozzle, there being no fuel chamber to which the fuel is first elevated as in these types of fuel lift carburetors known in the art.

Another object is to provide a carburetor having particularly novel means for maintaining the fuel discharge nozzle under the proper depression to assure the flow of fuel 25 thereto.

Another object is to provide a carburetor which has but few parts and which may be manufactured at a relatively low cost.

Other objects and advantages will herein-after appear.

An embodiment of my invention is illustrated in the accompanying drawings forming a part of this specification wherein:

Fig. 1 is a side elevation of a two-cycle portable gasoline engine equipped with my 30 improved carburetor;

Fig. 2 is an end elevation of the carburetor;

Fig. 3 is a sectional view along the line 3—3 of Figure 2;

Fig. 4 is an enlarged sectional view along the line 4—4 of Figure 2;

Figure 5 is an enlarged sectional view along the line 5—5 of Figure 3, and

Fig. 6 is an enlarged view of a part of 50 the mechanism as illustrated in Figure 3.

The carburetor selected for illustration herein is designed for use on a small gasoline engine such as used for driving washing machines and similar small machinery in the private home or shop.

In general the carburetor comprises a die cast body A having an induction passage B, one end of which is adapted for communication with the inlet manifold of the engine C and the other end of which is open to 55 atmosphere. A fuel nozzle D in the form of a suction multiplying Venturi tube discharging into the passage B functions to lift fuel from the tank E directly thereto where it unites with the air streams passing through 60 the nozzle and passage B to form a properly proportioned fuel mixture. A choke F is employed for starting the engine and functions 65 automatically as the engine cranking pedal G is operated. The carburetor also is provided with a valve H operable automatically to admit air to the passage B when the choke 70 F is closed and the engine has started to run. An air valve J of novel construction is employed to control the condition of depression 75 in that portion of the passage B, with which the nozzle D communicates.

The induction passage B is uninterrupted throughout its length except for air valve J. This valve is placed immediately beneath the 80 discharge orifice of the nozzle D and is pressed against its seat 10 by a spring 11 to close the passage B. The valve yields to the differential in pressure between atmosphere and engine manifold suction to permit the 85 induction of air through the passage B. An upstanding stem 12 centrally located upon the valve carries at its upper end a disc 13 which rests slightly above the discharge orifice of the nozzle D when the valve is closed. 90 The disc partially isolates that region of the passage B immediately above the valve and surrounding the orifice of the nozzle D from the upper section of the passage which section is normally at atmospheric pressure so that a sufficient depression is maintained in the nozzle region of the passage to assure the subjection of the fuel nozzle to depression 95 sufficiently low to induce the elevation of fuel from the tank E thereto.

The fuel in passing from the tank E to the fuel nozzle is first conducted through a strainer cap 15 which is disposed at the lower end of a tube 16 extending within the tank and which communicates at its upper end with passages 17 within the body of the carburetor by a detachable fitting 18. This fitting is employed to permit the ready removal of the tube and strainer cap for cleaning. The passages 17 communicate with an adjustable needle valve 18a which is set by movement of a wing lever 19 to control the quantity of fuel which may be drawn to the fuel nozzle D at a predetermined depression. A short passage 20 between the valve and the throat 21 of the nozzle D completes the fuel conducting course.

Means for preventing the fuel in the tube 16 from seeking a common level with the fuel in the tank E when the engine is stopped is provided in a disc check valve 25 forming a part of the fitting 26 upon which the strainer cap 15 is mounted. The valve 25 also serves to prevent back flow of the fuel which might occur during the compression stroke of the engine.

In order to facilitate the starting of the engine C by providing a rich fuel charge the choke F is employed. This choke comprises a shutter 30 which is pivoted about a sleeve 31 within which the needle valve 18a is mounted so that it may be rotated upon its mounting to entirely close the inlet opening 33 of the induction passage B and therefore causes a rich fuel discharge such as is necessary in first starting the engine. An arm 35 formed integral with the shutter 30 is mechanically connected by a link 36 to the cranking pedal G beyond its fulcrum 37. Thus when the cranking pedal is depressed to crank the engine the choke F closes.

The cranking pedal G may be constructed for either foot or hand actuation and has formed at its remote end a segmental gear 39 which meshes with a gear 40 carried by and connected with the engine shaft 41 through suitable mechanism.

In order to prevent the engine from becoming choked after it has fired and started to run under its own power, should the operator retain his foot or hand upon the starting crank pedal thus holding the choke closed, a valve H which under all normal conditions remains closed, will open by atmospheric pressure to admit air in sufficient quantities to prevent the engine from becoming choked up and stopping. I have therefore provided a foolproof starting choke mechanism with which successful initial engine operation is assured though the operator may know nothing about its presence or function.

In operation my improved carburetor requires little attention, namely, the adjustment 65 of the needle valve 18a, by movement of the

wing lever 19 to meet speed and load conditions.

In starting the engine the operator has only to depress the cranking pedal G, whereupon movement of the segmental gear 39 therewith causes the engine shaft 41 to rotate. By the same movement of pedal G the choke F will close the induction passage inlet 33 to cause a rich fuel charge to be drawn into the engine manifold, thus causing the engine to fire and run under its own power.

If now the operator should continue to hold the pedal G depressed either through thoughtlessness or without knowledge of the fact that the choke is thus held closed, the increased depression in the induction passage B caused by the running engine will result in the opening of valve H by atmospheric pressure to admit sufficient air to prevent the engine from choking up and stopping.

At all times during operation of the carburetor that region of the passage B surrounding the fuel nozzle D is maintained at a higher depression than the posterior section of the passage because of the disc 13. This simple arrangement permits the disposition of the nozzle D to the rear of the air valve J instead of in front of it as in the present known types of carburetors employing a Venturi tube for the fuel nozzle. The arrangement makes for a very simple yet efficient fuel lifting mechanism which may be maintained at very low cost and which is highly compact.

I claim:

1. A carburetor having an induction passage adapted for communication at one end with the intake manifold of an internal combustion engine and open to atmosphere at the other end, a fuel nozzle discharging into said passage, a choke for closing said open end of said passage to induce a rich fuel discharge for starting the engine and means operable automatically upon the increase in engine manifold suction as the engine runs under its own power for admitting sufficient air to said passage to sustain engine operation only when the choke is left in closed position after the engine has started.

2. In a carburetor having an induction passage, the outlet of which is adapted for communication with the intake manifold of an internal combustion engine and the inlet of which is open to atmosphere, an air valve in said passage adjacent to its outlet and arranged to yield to the differential in pressure at opposite sides thereof, a fuel nozzle having its discharge orifice communicating with said passage immediately behind said valve and means associated with the valve forming a partially closed chamber adjacent the nozzle for causing a relatively higher depression in that region of the passage immediately surrounding the discharge orifice of said nozzle than exists in the remaining portion of

the passage between the valve and the passage inlet.

3. In a carburetor having an induction passage, the outlet of which is adapted for communication with the intake manifold of an internal combustion engine and the inlet of which is open to atmosphere, an air valve in said passage adjacent to its outlet and arranged to yield to the differential in pressure at opposite sides thereof, a fuel nozzle having its discharge orifice communicating with said passage immediately behind said valve and means associated with the valve forming a partially closed chamber adjacent the nozzle for causing a relatively higher depression in that region of the passage immediately surrounding the discharge orifice of said nozzle than exists in the remaining portion of the passage between the valve and the passage inlet, said means also serving as a stabilizer for said valve to prevent the valve from chattering in response to slight fluctuation in manifold suction.

4. In a carburetor having an induction passage, the outlet of which is adapted for communication with the intake manifold of an internal combustion engine and the inlet of which is open to atmosphere, an air valve in said passage adjacent to its outlet and arranged to yield to the differential in pressure at opposite sides thereof, a fuel nozzle having its discharge orifice communicating with said passage immediately behind said valve, and a disc of less diameter than said passage disposed parallel to said valve and carried thereby, said disc lying between said fuel nozzle discharge orifice and said passage inlet to form a partially closed chamber adjacent the nozzle whereby that region of the passage surrounding said nozzle orifice is maintained at a higher depression than the remaining section thereof during normal carburetor operation.

5. In a carburetor including an induction passage having its outlet end communicating with the intake manifold of an internal combustion engine and its inlet end open to atmosphere, an air valve in said passage adjacent said outlet end operable by the differential in pressure at opposite sides thereof, a fuel nozzle discharging in said passage immediately behind said valve and means associated with said valve for partially closing said passage adjacent the fuel nozzle for causing a relatively higher depression in that portion of the passage between said valve and its associated means surrounding the discharge end of the fuel nozzle than exists in the remaining portion of the passage between said means and the inlet passage.

6. In a carburetor including an induction passage having its inlet end open to atmosphere and its outlet end communicating with the intake manifold of an internal combustion engine, an air valve in said passage adjacent

said outlet end operable by the differential in pressure at opposite sides thereof, a fuel nozzle discharging in said passage immediately behind said valve and a disc integral with said valve and spaced therefrom, said disc lying across said passage between the discharge end of said fuel nozzle and the passage inlet to form a partially closed chamber adjacent the nozzle whereby the same is maintained at a higher depression than the remaining portion of the passage during the normal carburetor operation.

In witness whereof, I hereunto subscribe my name this 15th day of July, 1929.
